Primary Examiner — R. Johnson(74) Attorney, Agent, or Firm — Sughrue Mion, PLLC(57) CLAIM

The ornamental design for an electric guitar, as shown and described.

DESCRIPTION

FIG. 1 is a perspective view of an electric guitar showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the electric guitar is included for the purpose of illustrating portions of the electric guitar and forms no part of the claimed design.
